UNITED STATES PATENT OFFICE.

CLARENCE L. DEWEY, OF WILMETTE, ILLINOIS, ASSIGNOR TO CEMENT GUN CONSTRUCTION CO., OF CHICAGO, ILLINOIS, A CORPORATION OF ILLINOIS.

DEVICE FOR FEEDING COMMINUTED MATERIAL TO A CONDUIT.

Application filed February 23, 1923. Serial No. 620,667.

To all whom it may concern:

Be it known that I, CLARENCE L. DEWEY, a citizen of the United States, residing at Wilmette, in the county of Cook and State of Illinois, have invented certain new and useful Improvements in Devices for Feeding Comminuted Material to a Conduit, of which the following is a specification.

This invention relates to a device for feeding comminuted material to a conduit.

In the use of the cement gun, sand and cement are fed into a conduit by a suitable device and the use of air under pressure, and are projected from the conduit with water, whereby the mixture is hydrated and subsequently combined into mortar.

In such devices heretofore used, there is no provision made for cleaning the hose or conduit of masses that may accumulate therein to an extent that substantially closes the hose.

Furthermore the charge containing wheel into which charges of sand and cement are deposited does not make air tight connection with the feeding means, resulting in considerable loss of air and variation of pressure.

My improved device overcomes the above mentioned objections without changing the principle of operation of said prior device and provides additional means by which to apply the full force of the air under pressure to the cleaning operation and convenient means for packing the relatively moving parts containing the sand and cement.

One of the objects of the invention is to improve feeding and cleaning devices for cement guns.

Another object is to provide, in a device of the character described, means for bypassing the feeding device and applying the full pressure of air to the conduit to clean it.

A further object is to provide an improved means of packing the charge-containing wheel and the feeding device as the pockets of the wheel are brought, in turn, under the feeding device.

Another object is generally to improve devices of this character.

Other objects and advantages will hereinafter appear.

In the drawings:—

Fig. 1 is a longitudinal central section taken substantially on line 1—1 of Fig. 2.

Fig. 2 is a transverse section taken on line 2—2 of Fig. 1.

Fig. 3 is a section taken thru the cowl on line 3—3 of Fig. 1.

Fig. 4 is a transverse section thru the cowl taken on line 4—4 of Fig. 3.

Fig. 5 is a plan view of part of the charge holding feed wheel.

In all the views the same reference characters are used to indicate corresponding parts.

I have shown only parts of the device which are directly concerned with the feeding mechanism. The means for driving the parts; for compressing air and for loading the charge-containing wheel are not of present interest.

A part 10 of the frame which supports the charge-containing wheel 11 also supports a fitting 12 secured thereto by proper means.

There is an opening 13 in the frame 10 closed by the fitting 12 and thru which a cowl-like part 14 projects.

The wheel 11 is driven intermittently and stops at the end of each movement with a pocket 15 immediately under the cowl 14 as shown in Fig. 1. The pockets between the partitions 15 of the wheel 11 are loaded with sand and cement to be introduced or blown into the hose or conduit 16. A conduit 17 communicates with the cowl 14 and thru a hose or pipe 18 it is to be connected to a source of air supply (not shown) which furnishes air under pressure to shoot or blow the cement and sand thru the conduit 16.

There is an opening 19 which continues thru the rotary valve 20 into the pocket 15. There is a by-pass 21 between the passage 17 thru valve opening 20 to the conduit 16. This by-pass is shown to be closed so that the air from 17 will blow the charge to be contained in pocket 15, thru valve 20 into conduit 16 with the valve handle 22 in position shown in full lines.

When it is desirable to clean the hose the handle 22 is raised to vertical position, shown in broken lines, whereupon communication between 15 and 16 will be closed and communication between 16 and 17 directly established thru port 21 and port 21'.

A sheet of yielding material, such as leather or rubber 24 is placed around the cowl 14 with its lower edge in substantial

contact with the upper edge of the wall of the cowl 14 partly surrounding each pocket, to prevent the air from escaping from the air conduit. The sheet 24 is held in place by a strap 25 and screws 26.

Having described my invention what I claim as new and desire to secure by Letters Patent, is:—

1. A device of the character described comprising a charge holder for comminuted material; a conduit thru which the material is to be passed; means for introducing air under pressure to move the charge and a valve arranged to close the charge-holding container and to by-pass the container providing a direct path into the conduit.
2. A device of the character described

comprising a rotatable wheel having a plurality of charge-holding pockets, intermittently moved to an extent equal to the width of a pocket; a cowl overlying the successively positioned pockets; a yielding packing to close the space between the cowl and positioned pockets; a conduit in communication with the positioned pocket; an air conduit communicating with the cowl to blow a charge into the conduit and a valve to connect the two conduits together and to by-pass the cowl and the charge-holding pocket.

In testimony whereof I hereunto subscribed my name.

CLARENCE L. DEWEY.
